UNITED STATES PATENT OFFICE.

CHARLES E. HEARD, OF WASHINGTON, DISTRICT OF COLUMBIA.

FLASHING AND FASTENING STRIP FOR ROOFS.

1,218,937.

Specification of Letters Patent.

Patented Mar. 13, 1917.

Application filed October 4, 1916. Serial No. 123,737.

To all whom it may concern:

Be it known that I, CHARLES E. HEARD, a citizen of the United States, residing at Washington, in the District of Columbia, have invented certain new and useful Improvements in Flashing and Fastening Strips for Roofs, of which the following is a specification.

My invention relates to the construction 10 of buildings and more particularly to means applicable to a variety of purposes, as for instance for use on all roofs and ledges where flashings are required to prevent the entrance of moisture and for securely fastening metallic roofs and preventing such roofs from becoming loose and blowing off.

Among the objects in view is to provide a simple, inexpensive and efficient means adapted for flashing purposes and also for 20 securing a roof of a building without danger of said roof working loose and blowing off and to avoid the use of nails and boards such as have heretofore been used generally, and said means being so constructed as to 25 permit the expansion and contraction of the roof and to allow for settlement of the building.

A further object is to provide means as heretofore referred to which is adapted to 30 be laid in the brick or stone-work while the latter is being erected and held permanently in place without the use of nails or boards.

A further object is to provide means as 35 heretofore referred to adapted for securing flashings in position around any projection extending above the roof line and allowing for expansion and contraction of the roof and flashing.

40 A further object is to so construct the device that the same is adapted to quickly cut away the mortar or cement between courses of brick or stone when said device is to be inserted in position in old buildings.

45 Other objects and advantages of the invention will appear from the following description when taken in connection with the accompanying drawings.

The invention consists in the novel construction of the device, all as hereinafter fully described, illustrated in the drawings and pointed out in the appended claims.

In the drawings:

Figure 1 is a vertical sectional view illustrating the invention as applied for securing a flashing around a fire-wall chimney or

other projection extending above the roof line.

Fig. 2 is an enlarged perspective view, and Fig. 3 a sectional view of a portion of 60 the device seen in Fig. 1.

Referring to the drawings, 15 indicates my device consisting of a strip made of any desired metal, preferably galvanized iron, and having any suitable length. The strip 65 is bent longitudinally along the line 16 at a right angle, whereby to form the wide flange 17, and also the flange 18 which latter is bent or folded under and upwardly along the line 19 to form the portion 20, and the latter portion is then bent or folded 70 downwardly to form an apron 21, which forms a groove 24 between it and the portion 20. The apron 21 is deeper than the portion 18, it extending between one-fourth 75 and one-half an inch below the edge 19 to form a guide to facilitate the insertion of the bent-up edge of the roof or flashing.

The strip 15 is provided with a series of cut-away portions or recesses 22 to form 80 teeth 23. These teeth enable the device to be used in the manner of a saw for cutting away mortar or cement between courses of brick or stone in old buildings by holding the teeth against the mortar or cement and 85 then reciprocating the device whereby the teeth soon cut a mortise or slot of a depth sufficient to allow the flange 17 of the strip to be inserted in said slot. The device is then securely retained in place by pointing 90 up the slot with mortar or cement.

When the device is to be applied on new buildings while in course of construction, the portion 17 is laid flatwise on a course of bricks or stone at the proper point with 95 the twice-folded flange 18 projecting downwardly, and then mortar or cement is laid upon the portion 17 and a course of bricks or stone is laid in the mortar or cement. Longitudinal movement of the strip is also 100 prevented by the teeth by reason of the device being embedded in the mortar or cement.

For the purpose of still further securing the strip between courses of bricks or stone, I may provide said strip with a series of openings 24' of any desired outline and when the mortar or cement is laid upon the portion 17 it will enter said openings and form keys when set.

110 The strip 15 is primarily intended for securing a flashing of a roof around a chim-

ney or other projection extending above the roof line, as indicated in Fig. 1, and also for use where buildings intersect.

In Fig. 1 I show the flashing 26 as being bent upwardly and extending within the groove 24. By this method of securing the flashing the latter cannot pull out and it avoids the entrance of moisture behind the flashing strip.

10 Also, contraction and expansion of the roof and settlement of the building are provided for. No soldering or nailing of the flashing is necessary and a saving in the cost of such nails and also in the labor involved

15 is effected.

The strip 15 is to be secured in place at any point above the roof line, preferably six inches or more.

My device can also be used for fastening 20 roofs securely, and when so used the roofing is bent over the outside of a wall and then downwardly, and its edge is then bent upwardly so as to enter the groove 24. In this manner the roof will be locked securely in 25 position and cannot become loosened or blown off. Furthermore, this mode of fasten-

ing the roof avoids the use of nails, boards, laths, and mortar as heretofore used for the purpose and effects a great saving in the cost of laying a roof.

30

What I claim and desire to secure by Letters Patent is:

A flashing comprising a strip having a wide flange for insertion between the courses of masonry, said flange having a toothed 35 edge facilitating its insertion by a sawing action in masonry already in place and tending to prevent longitudinal movement of the strip when built into a wall, and said strip also having a flange bent at an angle 40 to the first-named flange and having a portion twice folded upon itself to form a depending rib and an adjacent groove and then extending below the rib to form an 45 apron.

In testimony whereof I affix my signature in the presence of two witnesses.

CHARLES E. HEARD.
